UNITED STATES PATENT OFFICE.

OWEN K. VANSANT, OF PHILADELPHIA, PENNSYLVANIA.

FUEL-MIXING DEVICE.

Application filed August 16, 1921. Serial No. 492,758.

The herein described device relates to fuel-mixing device for use in automobiles and one of the objects of the said invention is to provide means for the continuous vaporizing and breaking up of the condensed fuel particles in the fuel mixture passing to the motor, to such consistency as will be the means of an automobile running more smoothly, with the use of less fuel mixture, and to prevent "knocks."

The herein described device is inexpensive to manufacture, readily applied to any make automobile, has no loose parts to become separated, worn or destroyed in any manner.

While the foregoing explains the general purpose and objects of the device, other objects and advantages will appear in the specifications that follow, in which the novel features, construction and arrangements of the various parts will be brought out, described and claimed.

In the accompanying drawing, forming a part of this specification, and in which corresponding parts are denoted by like designating numerals is illustrated the preferred form of the embodiments of the invention capable of carrying the same into practical operation, it being understood that the invention is not necessarily limited thereto, as various changes in shape, proportions and general assemblage of the several parts may be resorted to without departing from the principle of the invention or sacrificing any of its advantages, in which:

Figure 1 is a view of the device in connection with carburetor.

Figure 2 is a plan view of the device.

Figure 3 shows the device in section on the line 3—3, Figure 2.

Figure 4 is a view in section.

To more fully describe the drawings, and to make clear the operation and the purpose of the herein described device:—

The letter A shows the device which is a one piece cast; the numeral 1 shows a flexible tube leading from the hot air manifold and leading into heating chamber 2; 3 is top of baffle-plate; 4 shows the apertures through which fuel mixture enters into motor; 5 shows projections which assist in breaking the fuel mixture heating the same and throwing the resultant spray against the baffle plate 6 with the downwardly pro-

jecting members; 7 shows flexible tubing leading into heating chamber of carburettor; 55 8 is the passageway for the fuel mixture; 9 are stud holes for securing the device between carburettor and manifold. The carburettor is shown by the letter B with the device located at the top most portion thereof.

In operation:—the hot air passes through the flexible tubing 1 into heating chamber or passage 2 and heats the same as well as the baffle plate 3 with the downwardly projecting members 6 and the arms 3'. The fuel mixture enters the passage 8 and is thrown against the fuel mixture guides 5 and being partially broken and vaporized thereby, and being drawn upwardly against 70 the downwardly projecting angular shaped members diverging from a narrow central plane and becoming larger at the periphery 6 which still further heats and breaks the condensed fuel into a vaporized state and flowing through the apertures 4 into intake manifold. By the arrangement of the heating chamber 2 the hot air makes a continuous circulation therethrough and into tubing 7 and back into carburettor chamber, a feature not hitherto provided in devices of like nature and causes a continuous heating of the baffle plate 6 and thereby causing an additional means for breaking the condensed particles of fuel and vaporizing the 85 same.

It is to be noted that the device is so constructed that there are no removable parts to become worn, broken, lost or removed, and is adapted to be used on any make of 90 automobile.

What I claim as new and desire to secure by Letters-Patent is:—

1. In a fuel mixing device, a main body portion, a chamber for the heating of fuel mixture on the inner side of said body portion, an inner chamber spaced from said mentioned chamber partially closed at the upper extremity and forming a second chamber of greater width at the upper extremity than at the lower extremity forming in connection with an upper partially open plate with the under side having a contour materially different to that of the upper side and means for the outlet of the spray resulting from the baffles situated centrally. 100 105

2. In a fuel mixing device, a main body portion, a chamber inside the said main body portion through which is circulated heated air, an opening in the inner or central portion thereof, a divisional member with the lower portion of greater width than that of the upper central portion and extending up-

wardly and inwardly for a determined space into a chamber capped by a divided upper member of which the contour of the upper outside is materially different to that of the inner lower portion. 10

In testimony whereof I affix my signature.
OWEN K. VANSANT.
